UNITED STATES PATENT OFFICE

2,634,075

STAND

Mary J. Mayzel, Lansford, Pa., assignor of fifty
per cent to Alphonso P. Citro, Summit Hill, Pa.

Application October 27, 1949, Serial No. 123,826

5 Claims. (Cl. 248—170)

1

This invention comprises novel and useful improvements in a stand and more specifically pertains to a collapsible stand having improved means for retaining the parts in their assembled and in their collapsed positions as desired.

The principal object of this invention is to provide an improved construction of stand which may be employed for a support for various articles, and which shall have an improved construction permitting ready collapsing or folding of the stand into a compact position for storage or for assembling into an operative position.

A further object of the invention is to provide an improved stand in conformity with the foregoing object wherein the legs of the stand are provided with improved means for selectively locking the same into their operative and inoperative positions.

Yet another object of the invention is to provide an improved stand which shall be of a simple and inexpensive construction, yet sturdy and highly efficient for the purposes intended.

These, together with various ancillary features and objects of the invention which will later become apparent as the following description proceeds, are attained by the present invention, a preferred embodiment of which has been illustrated, by way of example only, in the accompanying drawings, wherein:

Figure 1 is a perspective view of the preferred embodiment of the invention shown in its erected and operative position;

Figure 2 is a vertical central sectional view taken substantially on the plane of the section line 2—2 of Figure 4 and showing the position of the parts of the stand in the collapsed or folded position of the same;

Figure 3 is a horizontal sectional view of the stand in its operative position, taken substantially on the plane of section line 3—3 of Figure 6;

Figure 4 is a horizontal sectional view taken substantially on the plane of the section line 4—4 of Figure 2 and showing a detail of the stand in its collapsed position;

Figure 5 is a view similar to Figure 6, showing the lower portion of a modified form of the stand in its operative position;

Figure 6 is a view similar to Figure 5 showing the lower portion of the stand of Figure 1 in its operative position;

Figure 7 is a perspective view of a portion of one of the legs of the stand of Figure 1;

Figure 8 is a horizontal sectional detail view taken substantially upon the plane of the section line 8—8 of Figure 5;

Figure 9 is a perspective view of a portion of the leg employed in the embodiment of Figure 5; and,

Figure 10 is a further fragmentary detail perspective view.

2

Referring now more specifically to the accompanying drawings, wherein like numerals designate similar parts throughout the various views, attention is directed first to the embodiment of Figures 1—4, 6, 7, in which it will be seen that the foldable stand forming the subject of this invention consists of a pair of concentric inner and outer tubes, or sleeves, 10 and 12, which are relatively slidable with respect to each other. The lower end of the outer tube or sleeve 12 is provided with a closure cap or base 14, having an upstanding annular wall 16 which is received within the lower end of the outer sleeve 12 and secured thereto in any desired manner. The upper surface of this annular wall 16 of the base 14, constitutes a seat or abutment upon which the lower end of the inner sleeve 10 may rest.

Embracing the bottom portion of the exterior surface of the outer sleeve 12 is a metal strap or band 18 which is clamped or otherwise fixedly secured to the outer sleeve in any suitable manner, this band having a plurality of radially extending pairs of apertured ears 20 between which are pivotally attached supporting legs 22 of the stand.

As shown best in Figure 7, these legs may conveniently comprise tubular rods having flat portions 24 at their inner ends, these flattened portions being apertured as at 26 for the reception of pivot pins 28 by means of which the flattened portions are pivotally secured between the pairs of ears 20. By this means, the legs are mounted for vertical pivoting movement between the folded, vertically extending position shown in Figure 2 and the horizontal, operative position shown in Figure 1.

Adjacent its hinged extremity, each leg 22 is preferably provided with a laterally extending lug 30 which adjacent the leg 22 is provided with a slotted portion 32 by means of which the leg may be locked in its closed or folded position, and with a laterally extending surface 34 constituting an abutment surface by means of which the leg may be locked into its opened or operative position.

The outer sleeve 12 and the annular wall or rim 16 of the base secured therein, are provided with vertically extending slots 36 which are adapted to receive the lug 30 when the leg is folded into its closed position.

Freely and slidably received upon the outer sleeve 12 is a retaining or locking sleeve member 38, having an annularly enlarged apron-like lower portion 40 which is adapted to embrace the flattened end portions 42 of each of the leg members in their raised position as shown in Figure 2 to thereby retain and lock these legs in their collapsed arrangement. At the same time, the lower edge of the inner sleeve 10 in its lowered position will engage in the notches 32 of the legs in their folded position, as shown in Figure 2, whereby

the legs are locked at both their extremities and the entire stand is thus retained in its collapsed position.

It will now be seen that in order to convert this stand from its folded or inoperative position shown in Figure 2 to the operative position of Figure 1, it is merely necessary to raise the retaining sleeve 38 whereupon the apron portion 40 will disengage its locking embracing of the ends of the legs, and upon raising of the inner sleeve 10, whereby the lower end of the same will be disengaged from the slots 32, the legs will pivot vertically by means of their own weight to their horizontal position shown in Figure 1. At this time, the retaining sleeve may be dropped to its lower position, whereupon the exterior surface of the apron 40 will be disposed against the abutment surface 34 of the legs, thereby preventing the legs from raising above their horizontal position. At the same time, the hinged extremities of the legs which are arcuately shaped as at 44, will engage the regularly extending stops or abutments 46 formed upon the rim portion 16 of the base, these stops extending through the above mentioned longitudinal slots 36. The engagement of the abutment surfaces 44 of the legs with the stop members 46 will prevent pivotal movement of the legs below their horizontal position. Thus, the legs will be securely locked against upward or downward pivoting movement, thus forming a very rigid and sturdy stand which may be employed to support any desired type of article.

Alternatively, the construction illustrated in Figures 5, 8 and 9 may be employed. In this form, the same construction of concentric inner and outer sleeves 12 and 10 may be employed, together with the retaining sleeve 38 having the retaining apron 40 thereon. Likewise, the annular clamp 18 having the pivots 28 for pivotally connecting between the pairs of radially extending pairs of ears to vertically pivoting leg members 50 may be employed. These leg members, however, as shown in Figure 9, are provided with flattened extremities 52, and curved abutment surfaces 54 and a pivot aperture 56, have omitted therefrom the locking lugs of the previous embodiment. Instead, a locking notch 58 is provided adjacent the pivot end of these legs, which at their other extremities are flattened in the same manner as the legs 22 at the ends 42 as shown in the preceding embodiment. In this embodiment, the legs are retained in their lowered, horizontal or operative position by engagement of the lower end of the apron 50 of the retaining sleeve 38 in the above mentioned notches 58, which thus positively prevents either upward or downward pivoting movement of the legs and locks the same in their operative position.

In the folded position, the legs are retained merely by the flattened outer end portions of the same being embraced by the apron 40 of the retaining sleeve 38.

From the foregoing, the advantages arising from the novel construction of the device, together with this operation will be readily understood by those skilled in the art after a consideration of the foregoing specification and accompanying drawings, and accordingly, further explanation is believed to be unnecessary. However, since numerous modifications and changes will readily occur to those skilled in the art after

a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A support stand comprising a pair of concentric, relatively slidable sleeves, a plurality of supporting legs pivoted to the outer sleeve for selective vertical movement to a lowered operative position and an upwardly folded inoperative position, said outer sleeve having slots, locking means carried by said legs adjacent the pivoted ends thereof and disposable through said slots and operatively engaging the inner sleeve in the upwardly folded position of the legs.
2. A support stand comprising a pair of concentric, relatively slidable sleeves, a plurality of supporting legs pivoted to the outer sleeve for selective vertical movement to a lowered operative position and an upwardly folded inoperative position, said outer sleeve having slots, locking means carried by said legs adjacent the pivoted ends thereof and disposable through said slots and operatively engaging the inner sleeves in the upwardly folded position of the legs, a sleeve slidably mounted upon the outer sleeve, said outer sleeve having a portion embracing and retaining said legs in their folded position.
3. A support stand comprising a pair of concentric, relatively slidable sleeves, a plurality of supporting legs pivoted to the outer sleeve for selective vertical movement to a lowered operative position and an upwardly folded inoperative position, said outer sleeve having slots, locking means carried by said legs adjacent the pivoted ends thereof and disposable through said slots and operatively engaging the inner sleeve in the upwardly folded position of the legs, a sleeve slidably mounted upon the outer sleeve, said last-mentioned sleeve having a portion embracing and retaining said legs in their folded position, said legs having reduced extremities for engagement by said last-mentioned sleeve.

4. The combination of claim 1 wherein said locking means comprises lugs carried by said legs and having notches for receiving an end of said inner sleeve.

5. The combination of claim 1 wherein said locking means comprises lugs carried by said legs and having notches for receiving an end of said inner sleeve, said lugs each having an abutment surface, said sleeve being movable into engagement with said abutment surfaces for limiting upward pivoting movement of said legs.

MARY J. MAYZEL.
